UNITED STATES PATENT OFFICE

ARTHUR O. AUSTIN, OF NEAR BARBERTON, OHIO, ASSIGNOR, BY MESNE ASSIGNMENTS,
TO THE OHIO BRASS COMPANY, OF MANSFIELD, OHIO, A CORPORATION OF NEW
JERSEY

CONDUCTOR CLAMP

Application filed March 12, 1929. Serial No. 346,384.

This invention relates to clamps for supporting electrical conductors or other cables, and has for one of its objects the provision of a supporting clamp which will gradually transfer the load on the cable to the clamp and avoid abrupt variations in the force transmitted.

A further object is to provide a clamp which will serve as a snubber or damping device to dampen out vibrations in the conductor.

A further object is to provide a cable support which shall be of improved construction and operation.

Other objects and advantages will appear from the following description.

The invention is exemplified in the combination and arrangement of parts shown in the accompanying drawings and described in the following specification, and it is more particularly pointed out in the appended claims.

In the drawings:

Fig. 1 is an elevation of a conductor clamp embodying one form of the present invention.

Fig. 2 is a section on line 2—2 of Fig. 1.

Fig. 3 is a fragmentary elevation showing a modification of the invention.

Fig. 4 is a section on line 4—4 of Fig. 3.

Fig. 5 is a fragmentary elevation of another modification.

Fig. 6 is a section on line 6—6 of Fig. 5.

Fig. 7 is a fragmentary elevation of a different modification.

Fig. 8 is a section on line 8—8 of Fig. 7.

Fig. 9 is a fragmentary elevation of another form of the invention.

Fig. 10 is a top plan view of Fig. 9.

Fig. 11 is an elevation of another modification.

Fig. 12 is a section on line 12—12 of Fig. 11.

Fig. 13 is an elevation of another modification.

Fig. 14 is a section showing another modified detail of construction.

In building electrical transmission lines, it is common practice to stretch conductors at fairly high tensions. By increasing the tension, the sag in the line can be diminished

and consequently the number of supporting structures may be reduced. Experience seems to indicate, however, that as the tension in the line is increased, there is an increased tendency for the conductors to vibrate which may cause serious damage from crystallization, particularly at the points of support. The vibration or oscillation of a conductor may be very large compared to the energy setting up the oscillation under ordinary conditions. This seems to be due to the cumulative effect of the energy producing the oscillation, as clamps or attachments ordinarily used provide little or no means for the absorption of energy tending to produce oscillation. In order to prevent damage at the clamp or point of attachment, improved conditions may be obtained by absorbing energy from the vibrating conductor and by picking up the load gradually at the point of support thus dissipating the energy in the oscillation and gradually tapering off the stress. This tends to eliminate any "hard spot" along the conductor support and prevents flexing of the strands in the conductor beyond the point where crystallization will take place. In addition to the above advantages, it is highly desirable to provide a clamp which may be attached to the conductor readily and which will not seriously lower the flashover voltage between conductor and ground.

In the form of the invention shown in Fig. 1, the conductor 10, which may be of reinforced aluminum, copper, bronze, steel, or other suitable material, is placed between a lower seat piece 11 and an upper seat piece 12. The seat pieces 11 and 12 conform to the conductor 10 on their inner surfaces and to spring members 13 and 14 on their outer surface. By providing additional spring members 15 and 16 on the lower side and 17 and 18 on the upper side, it is possible, not only to take up the load gradually from the conductor, but any vertical movement in the conductor will tend to cause the adjacent spring leaves to slide over each other and absorb energy in the manner characteristic of the leaf spring. The upper seat piece 12 together with the spring members 14, 17 and 18

18 may be very much shorter or even longer than the lower seat piece with its supporting springs. In general, the upper members will be shorter except in cases where it is desired 5 to produce considerable absorption of energy due to the friction between the parts in which case they may be made of equal length or longer than the lower seat member.

With the arrangement shown, it is possible 10 to transfer the load from the conductor to the supporting clamp gradually and, at the same time, all looseness between the clamp members and the conductor may readily be prevented. Any looseness, together with vibration, would permit of the battering of the conductor and the destruction of the same very quickly. By properly shaping the supporting spring leaves, however, the seat pieces 11 and 12 may be kept in contact at 15 all times. In order properly to transfer the load from the spring members to the insulator string or where the conductors are used for ground wires to the tower members, clamping members 19 and 20 are clamped to 20 the seat pieces and their supporting spring members by bolts 21. The seat pieces 11 and 12 may be formed of drawn or cast sections or may be made out of thin sheet material. Where the seat pieces are of fairly rigid section, 25 they are provided with a series of slots 22. This permits these members to flex with the conductor and supporting members. Through the central portion of the clamp, however, the seat pieces 11 and 12 will be 30 supported by the supporting spring members and the clamping members 19 and 20 so that they will be quite rigid and the slots may be eliminated. These slots may be uniformly 35 or otherwise spaced in accordance with the 40 amount of movement required. The ears of a clevis 23 are provided for attaching to the insulator or tower support.

It is evident that any number and type 45 of spring supporting members may be used to obtain the desired results. The spring members may be made to contact throughout their length or only at points desired. By spacing them far apart at the point of support and allowing them to touch at their extremities, greater slipping action will result for a given deflection due to a vibration on the conductor. This will result in a greater absorption of energy. Friction may be more definitely controlled by using liners between 50 the spring members which have a higher coefficient of friction or this material may be placed only at the ends where the movement may be greatest.

In the modification shown in Figs. 3 and 4, 60 the seat pieces are formed from strips of thin material, having their edges bent over and slotted to form sections 24 and 25, the portions 24 being bent to provide flat bearing surfaces for the springs 26 while their edges 65 engage the sides of the cable and the portions

25 curved about the cable and have their edges 27 bent back so as to form a bearing on the supporting spring member 26.

In the modification shown in Figs. 5 and 6, portions 30 of the seat conform to the conductor and portions 31 form bearings against the supporting spring pieces to maintain proper alignment. The various spring pieces together with the seat pieces may be prevented from moving in a sidewise direction by small interlocking projections 32.

The slots permitting flexure of the seat pieces may be varied in accordance with the amount of bending in the conductor as shown in Fig. 7, a section of which is shown in Fig. 80 8. A different means for providing flexure in the seat pieces is shown in Fig. 9, a plan of which is shown in Fig. 10. In this construction, the seat piece made of thin pressed material may be formed in a general U-shape 85 in cross section. It is evident, however, that a U-shaped section will be exceedingly stiff and will not give the desired result, but will concentrate the flexure at the point where the cable enters the seat piece. Where the seat piece is stiff it will either concentrate the stress or the bending will cause the seat piece to fail at some point, concentrating the flexing at this point and causing damage not only to the seat piece, but to the conductor members as well. The desired flexibility of the U-shaped section, however, may be provided by fluting or waving the sides. The open side of the U-shaped section is spread out at 33 and brought in at 34. It 90 will be seen that while the central portion of the U-shaped seat piece may be fairly smooth, the edges may be fluted to such an extent that seat may be readily flexed without exceeding the elastic limit.

The vibration damper scheme for limiting movement of conductors may be applied to dead-end clamps, rail bonds, or other devices where it is desired to prevent damage to the conductor from crystallization.

Figs. 11 and 12 show one form of the invention applied to a dead-end clamp designated generally by the numeral 60. The conductor 10 enters the clamp which has a grip piece 35 held by bolts 36. The clamp may be equipped with a snubbing groove 37 commonly used on many clamps or the conductor may enter into one of the compression types of terminals or clamps, the absorbing or stress controlling springs being applied to a clamp of this kind in a manner similar to that shown in Fig. 11 or any suitable mechanical method. The spring members 38, 39 and 40 are secured to the body of the clamp by a holding block 41 and bolts or cap screws 42.

The arrangement of parts in Figs. 11 and 12 is similar to that in the suspension clamps shown in Figs. 1 and 2. The seat piece 43 forms a suitable bearing between the spring 130

members and the conductor 10. Where it is desired to provide an absorption of energy due to the slipping of the spring parts upon each other and upon the seat piece 43, the 5 clamp may be equipped so that its mass may be increased by weight members 44. These members may constitute an integral portion of the clamp body or if made separable, the amount of weight may be changed to suit 10 different conditions.

Where it is desired to increase the energy absorption to dampen out or limit the vibration as much as possible, this may be done by constructing the damping means so that a 15 greater frictional movement will be produced by a given amplitude of vibration upon the incoming conductor. One form of construction for doing this is shown in Fig. 18. In this figure the spring members are separated 20 by spacers 45 and 46. This increases the angle between the spring members at their points of contact. As this angle is increased, a given vertical movement of the conductor 10 and the seat piece 43 will produce a greater 25 longitudinal slip between the adjacent spring parts so that the absorption of energy will be increased. In this case, the spring parts may run entirely free from each other to the points of contact at 47 and 48. The 30 absorption is still further increased by bearing or frictional pads 49 located between the spring members. These frictional pads have a double purpose in that they prevent wear between the spring parts and also increase 35 the coefficient of friction and the absorbing of energy for a given movement or slip between the parts. The bearing pads may be 40 of any suitable material such as fibre or a non-corrosive metal, such as aluminum, bronze, or other material.

The desired longitudinal friction may be increased even though the coefficient of the material is low by providing inclined surfaces for the bearing which will increase the effective pressure between the surfaces for a given 45 lateral pressure. This construction may be applied to vibration dampeners of other forms than those shown as, for instance, those shown in my prior applications, Serial Nos. 50 258,097; 258,445 and 266,584. In the arrangement shown in Fig. 14, spring members 50 and 51 are provided with friction shoes 52 and 53 having interfitting projections 54 and 55. The friction blocks 52 and 53 are fastened to the spring members 50 and 51 in any suitable way such as by projections 56 or by riveting or clamping in position.

It is evident that a scheme of this kind is 55 applicable as a vibration dampener and may be clamped to a conductor in any location where desired to prevent or limit the oscillation. Under these conditions, the dampener consists of the absorbing system together 60 with a mass so as to obtain relative movement and the necessary force to cause absorption.

While I have shown the damper arranged for suspension insulators and dead-end clamps, it is apparent that it may be applied equally well to other forms of insulator supports such as bus or pin type insulators or 70 to other structures that support flexible cables.

I claim:

1. The combination with a flexible conductor, of a support for said conductor, a 75 spring member secured to said support and having connection with said conductor at a point spaced from said support, and said connection comprising frictionally engaging surfaces that are moved upon each other by relative movement of said conductor and spring member for damping out movements of said spring member and conductor.

2. The combination with a flexible conductor, of a clamp for holding said conductor, and a spring finger extending from 80 said clamp along said conductor, said spring finger being spaced from said conductor adjacent said clamp but having frictional connection with said conductor at a point spaced from said clamp, said connection comprising frictionally engaging surfaces moved on each other by movement of said conductor.

3. The combination with a flexible conductor, of a clamp for supporting said conductor, a spring finger extending from said clamp along said conductor and a frictional member engaging said spring finger and having sliding frictional connection therewith 90 at a point spaced from said clamp for damping vibrations of said conductor.

4. The combination with a conductor, of a clamp for engaging said conductor, said clamp comprising leaf springs extending 95 along said conductor and having the surfaces thereon in relatively movable frictional engagement with each other to dampen out vibrations of said conductor, said leaf spring having open contour in cross section to facilitate bending thereof.

5. In combination a clamp for supporting a conductor, said clamp having a seat extending along said conductor and having graded resiliency for gradually taking up the load 105 on said conductor, and frictional means comprising relatively slideable frictionally engaging surfaces for damping movements of said seat imparted thereto by said conductor.

6. The combination with a conductor, of a channel shaped seat member engaging said conductor, said seat member having the side walls thereof sufficiently weakened at their edges to permit flexing under force exerted thereon by said conductor of said seat member.

7. The combination with a conductor, of a spring held channel shaped seat extending 120 along said conductor, and means for supporting said seat in a fixed position at one point 125 130

thereof, said seat having the walls thereof weakened at their edges to permit flexing of said conductor.

8. The combination with a conductor, of a clamp having a channel shaped seat engaging said conductor, said seat being open at one side to facilitate flexing thereof, a spring for supporting said seat against said conductor, and friction means comprising relatively sliding frictional engaging surfaces between said spring and said seat for damping vibrations of said conductor.

9. The combination with a conductor, of a channel shaped seat extending along said conductor, said seat having the side walls thereof weakened to permit flexing of said seat transverse to said conductor and leaf springs engaging said seat and graded in resiliency along the length thereof for gradually taking up the load on said conductor, said leaf springs having frictional engagement with one another for damping out vibrations of said conductor.

10. The combination with a conductor, of a clamp for holding said conductor in a fixed position at one point thereof, yielding fingers extending from said clamp along said conductor and graded in resiliency to take up gradually the load on said conductor, and means frictionally engaging said fingers and moved lengthwise thereof by vibrations of said conductor for damping out said vibrations.

11. The combination with a conductor, of a pair of channel shaped seat members disposed at opposite sides of said conductor, a clamp for holding said seat members, in contact with said conductor midway between the end of said seat members, said seat members having the side walls thereof weakened to permit flexing thereof, and a plurality of leaf springs held against the outer faces of said members by said clamp, said springs being graded in resiliency to take up gradually the load on said conductor and having frictional contact with one another for damping out vibrations of said conductor.

12. The combination with a conductor, of a channel shaped seat member engaging said conductor, a spring engaging said seat member for holding said seat member against said conductor, and interengaging means for preventing relative transverse movement of said spring and seat member.

13. The combination with a conductor, of a spring held channel shaped member engaging said conductor, said member having the sides thereof fluted at the edges to permit flexing of said member.

14. The combination with a conductor, of a channel shaped seat member engaging said conductor, said seat member having the sides thereof weakened to permit flexing thereof, the amount said sides are weakened being graded along said conductor to vary the flex-

ability of said seat member at different positions along said conductor.

15. The combination with a conductor, of a sheet metal channel forming a seat for said conductor, a spring engaging the face of said channel opposite said conductor, said channel having backwardly bent lugs thereon for engaging said spring to prevent relative transverse movement of said spring and channel.

16. The combination with a conductor, of a channel shaped seat member engaging said conductor, and a spring for holding said seat member against said conductor, the side walls of said channel having slots thereon to permit flexing of said seat member, the spacing of said slots being graded along said conductor to vary the flexibility of said seat member.

17. The combination with a conductor, of a vibration damper connected with said conductor, said damper comprising a pair of friction surfaces moved relative to each other by vibration of said conductor, said surfaces having interfitting projections and depressions for increasing the friction between said surfaces.

18. The combination with a conductor, of a clamp secured to said conductor and weighted to prevent movement thereof under the force of vibrations in said conductor, and a holding finger extending away from said clamp along said conductor, said finger comprising a U-shaped seat member having the side walls thereof weakened to permit flexing thereof, and a grading spring for holding said seat member in contact with said conductor.

19. The combination with a conductor, of a support for said conductor, a spring finger having one end thereof spaced from said conductor, said finger being inclined to the said conductor, and frictionally engaging means interposed between said conductor and the end of said spring finger nearest said conductor.

20. The combination with a strand, of a channel shaped spring member having said strand disposed within the channel thereof and extending only partially about said strand, and means for holding a portion of said spring member against transverse movement to cause said spring member to be flexed when said strand is vibrated.

21. The combination with a strand, of a channel shaped spring having said strand disposed in the channel thereof, said spring extending only partially about said strand, and means for holding said spring against transverse movement at one portion thereof to cause said spring to be flexed when said strand is vibrated, said spring having the edges thereof weakened to facilitate flexing of said spring.

22. The combination with a strand, of a channel shaped spring having said strand

disposed in the channel thereof, said spring extending only partially about said strand, means for holding said spring against transverse movement at one portion thereof to cause said spring member to be flexed when said strand is vibrated, the edges of said spring being undulated to facilitate flexing of said spring.

23. The combination with a strand, of a bar spring extending along said strand, means for holding said spring at one portion thereof against transverse movement relative to the adjacent portion of said strand, said spring being spaced away from said strand at the portion so held but having movable frictional connection with said strand at a point spaced from said held portion.

24. The combination with a strand, of a channel shaped spring member having said strand disposed in the channel thereof, means for clamping said spring member to the strand at one portion of said spring member, means for spacing said spring member away from said strand at the clamped portion thereof, said spring member having connection with said strand at a point spaced from said clamped portion, and means interposed between said spring member and strand at said last named point for affording frictional resistance to relative longitudinal movement of said spring member and strand produced by transverse vibration of said strand.

25. The combination with a strand, of a pair of leaf spring members clamped to said strand at one portion thereof and extending away from said clamped portion to provide resilient ends for gradually taking up transverse forces on said strand, said spring members having frictional connection with each other at a point spaced from the clamped portion thereof, and being spaced apart at the clamped portions thereof.

26. The combination with a strand, of a support for said strand comprising a leaf spring member disposed beneath said strand and clamped thereto but having a free end extending along said strand away from the clamped portion and disposed entirely below the longitudinal axis of the strand for gradually taking up the weight of said strand.

27. The combination with a strand, of a support for said strand comprising a leaf spring member disposed beneath said strand and entirely below the longitudinal axis of the strand and extending longitudinally thereof, means for clamping said leaf spring member to said strand at a point spaced from the end of said spring member, leaving the end portion of said spring member free to flex when said strand is vibrated vertically, and frictional means engaging said spring member for damping out vibrations thereof.

28. The combination with a strand, of a support for said strand comprising a pair of contacting leaf spring members disposed beneath said strand and entirely below the longitudinal axis of the strand and having frictional engagement with each other, means for clamping said spring members to said strand at a point spaced from the ends of said spring members to permit said spring members to take up gradually the weight of said strand and to allow vertical flexing of said spring members when said strand moves up and down, said spring members having frictional contact with each other to damp out vertical vibrations of said strand.

29. The combination with a strand, of means for damping vibrations of said strand comprising an open channel spring member having said strand disposed in the channel thereof, said spring member having the edges thereof undulated to facilitate flexing of the spring member.

30. The combination with a strand, of means for damping vibrations of said strand comprising an open channel shaped spring member having the edges thereof undulated to facilitate flexing of said spring member, and means having movable frictional connection with said spring member for damping vibrations of said strand and transforming the energy of such vibrations into heat.

31. The combination with a strand, of a spring having a portion thereof fixed in spaced relation to said strand, said spring being extended from said fixed portion along said strand at an angle thereto, and having frictional connection with said strand at a point spaced away from said fixed portion.

In testimony whereof I have signed my name to this specification this 11th day of March A. D. 1929.

ARTHUR O. AUSTIN.
